BOAT GEAR

Henry E. Rottmer, Washington, D. C.

Application April 28, 1943, Serial No. 484,896

8 Claims. (Cl. 9—45)

This invention relates to boat coupling gear by means of which life-boats, landing-boats, launches, etc., may be coupled to and released from the davit falls of a large vessel; and is an improvement over the device shown in Patent No. 998,263, granted July 18, 1911.

The above patent shows boat releasing gear wherein a hook member is positioned in the bow of a small boat and another in the stern; each having an extended shank adapted to be releasably held within a rotatable clutch collar, and the two collars connected by means of shafting for simultaneous movement upon actuation of an intermediately positioned control lever. This patent also provides means for operating either hook independently by means of mechanism located just below the hook. With the arrangement shown, the position of the collar, with respect to the connecting shafting, depends upon the degree of force which is exerted in screwing the stud into the shaft, and there is always a possibility that the gate openings in the two collars may not be in perfect alignment after the hooks have been independently operated. This will cause one hook to release before the other when the two are operated simultaneously.

It is the object of the present invention to provide boat-coupling gear of the general type disclosed in the aforementioned patent, in which at least two hooks are provided, adapted for simultaneous or independent operation, and designed to positively position the release clutch collars in open or closed positions and to automatically return the release collar to closed or locked position after it has been moved to open position independently of the others.

It is a further object of the invention to provide shock-absorbing means to cushion sudden strains to boat and falls incident to launching in a heavy sea. Frequently a boat will touch the crest of a wave relieving the falls of its weight, and, before the tackle can be released, the wave will have passed leaving the boat suspended over the trough. The quick falling away of the wave throws a terrific strain on boat and falls, resulting in many instances in buckling of the boat or parting of the fall ropes.

In general, it is the object of the invention to provide boat coupling gear in which the hooks may be operated separately or in unison to meet any given conditions, to protect the boat and gear from damage by shock or strain, and to provide means to ensure its operation under adverse or unusual circumstances.

Other objects will appear from the following

detailed description taken in the light of the drawings which accompany and form a part of this specification, and in which like characters of reference are used to designate like parts throughout.

In the drawings:

Figure 1 is a vertical longitudinal section through a life-boat equipped with boat coupling gear embodying the principles of the present invention, parts of the boat being broken away;

Figure 2 is an enlarged view of the ends of the boat shown in Figure 1, parts of the gear being shown in section;

Figure 3 is a plan view of the stem of the boat, the coupling hook, and connecting linkage;

Figure 4 is a horizontal section through the shock absorber pedestal looking down on the sliding cross-head, and is taken on the line 4—4 of Figure 2;

Figure 5 is a horizontal section through one of the rotatable locking clutch collars taken on the line 5—5 of Figure 2;

Figure 6 is a horizontal section through the clutch collar positioning means taken on the line 6—6 of Figure 2;

Figure 7 is an elevational view of a modified form of control means; and

Figure 8 is an end elevation of the control means shown in Figure 7.

Referring to the drawings in detail, a conventional life boat 1 is shown, having the usual stem 2, stern 3, and flooring 4. Closely adjacent the stem and stern vertical pedestals 6 are positioned, which are bolted or otherwise secured to the boat.

A rod 7 projects upwardly beyond the top of each pedestal 6 and has its upper end threaded into an upstanding member 11, which is bifurcated near its top to provide spaced ears 8, between which is pivotally mounted a coupling hook 9.

The hook 9 has a downwardly curving nose 10 which is offset near its lower end and terminates in a downwardly disposed pin 12.

The member 11 carries a bearing 13 in which is rotatably mounted a stub shaft 14 having a clutch collar 15 fixed to its upper end to releasably engage the depending pin 12 on the nose of the hook. Clutch collar 15 has an open side or gate 16, by means of which the pin 12 may pass into or out of the clutch collar. When the clutch

collar is rotated to a point where the gate faces the member 11, the pin is held against movement by the upstanding wall of the collar. When the collar is rotated 180°, or, in other words, when the gate 16 is diametrically opposed to the member 11 and in the plane of arcuate movement of

the pin 12, the pin will be free and the weight of the boat hanging from the falls 17 will cause the hook to rotate, releasing the falls from the hook.

The clutch collar stub shaft 14 is reduced in width just below the bearing 13, and the reduced end 18, which is of substantial length, is squared to telescopically fit into the interior of a length of hollow, squared shafting 19. The lower end of shafting 19 receives the squared end 20 of a section of shaft 21 having a round lower portion projecting below the end of shafting 19. Pins 47 pass through the shafting 19 and squared shaft 20 to secure the two together.

The round lower portion of shaft 21 is inserted into a sleeve 45, notched as at 22, the sides of the notch coacting with the sides of a similar notch 23 formed in the upper end of a similar inverted sleeve 46. Shaft 21 is secured to sleeve 45 by means of pin 48, and sleeve 46 is secured to a stud 50 by means of a pin 49. Stud 50 is round and projects upwardly completely through sleeve 46 and rotatably fits within sleeve 45, furnishing a bearing for the sleeve 45 and maintaining the shafting in alignment. The interfitting notches 22 and 23 of the sleeves 45 and 46 serve as a limit stop to position the clutch collar with respect to the main operating shaft and to permit exactly 180° of relative rotation between the upper and lower sections of the clutch collar control shafting.

An operating handle 24 is threaded or otherwise secured to the shaft 19 by means of which the shaft may be turned. A relatively heavy spring 25 is coiled about the shafting, having one end anchored to pin 48 which projects beyond the outer surface of the sleeve 45, and its other end fixed to the pin 49 projecting from the sleeve 46, the spring being biased to normally hold the clutch collar in its closed or locked position. By reason of the movement provided by the interfitting notches 22 and 23 of the sleeves 45 and 46, the clutch collar can be rotated to release position against the tension of the spring 25, and without movement of the sleeve 46. When the operating handle is released, the sleeve 45, the shaft 19, the stub shaft 14, and the clutch collar 15 moving as a unit will automatically return to their original positions with respect to sleeve 46 and associated shafting, with the collar having its gate 16 facing the rod 7, in which position the hook is locked in the collar. The abutting edges of the notches 22 and 23 limit the rotation of the sleeve 45 and so serve to precisely position the clutch collar in hook-release or hook-locked position.

A cylindrical casting 51, shown best in Figure 6, rather loosely surrounds the interfitting sections of the sleeves 45 and 46 and also the spring 25 to maintain the sleeves in alignment. Side plates 52 extend from the casting 51 by means of which the casting may be secured to the pedestal 6. Any longitudinal stress upon the shafting will be compensated for by movement of the telescopic joint formed by shafting 18 and 19 and there will be no up-and-down movement between the sleeves, as the spring 25 holds them together.

The above structure is employed at each of the hooks, and the ends of the studs 50 are fitted with universal joints 26 and interconnected in the usual manner by means of shafting 27. A control lever 28 is fixed to the shaft 27 amidships, by means of which all of the hooks may be operated simultaneously. Movement of the control lever 28 rocks the interconnecting shafting 27

which imparts rotation to the sleeves 46 and, as the sides of the notches 23 are normally held by spring 25 in position abutting the sides of the notches 22, the shafts 19, stub shafts 14, and clutch collars 15 are also rotated. Thus by movement of the control lever 28 all of the hooks may be released in unison, or by movement of the operating handles 24 individual hooks may be released independently of the others.

With this construction, one end of the boat may be released when the boat is to be towed. One man can connect the boat to the davit falls by opening each hook in turn, the clutch collars automatically locking the hook in place when the operating handle is released and automatically positioning itself for proper release simultaneously with the other hooks when the control lever 28 is actuated. Thus the human element is entirely eliminated in regard to positioning the clutch collars, and the safety factor consequently increased.

To prevent sudden shocks from tearing the gear from the boat or otherwise damaging the boat or lowering tackle, shock absorbing means are employed whereby the coupling hooks are yieldingly connected to the boat to cushion such stresses.

Pedestals 6 comprise vertical spaced supporting members 29 secured at their bottoms to the keel 30 of the boat and having a right angular offset 33 at their upper ends whereby they may be fastened to the boat's stem or stern. A bridge piece 30 connects the upper edges of the members 29 and is provided with an elongated opening 34 through which rod 7 passes. A compression spring 31 surrounds the rod 7, its upper end bearing against the bridge piece 30 and its lower end abutting a cross-head 32 held on the bottom of the rod by nuts 55. The cross-head 32 is notched on either side, as at 56, to slide upon the side members 29 of the pedestal 6. The notches 56 are slightly wider than the members 29, for a reason to be later explained. Although only one rod and spring is shown for each shock absorber, it will be readily understood that the load may be divided between two or more springs, if desired. By reason of the telescopic connection between the stub shaft 14 and the clutch collar operating shaft 19, the hook and clutch collar may move upwardly, compressing the spring 31 when sudden stress is thrown upon the launching tackle. Although the clutch collar moves with the hook to maintain the relative position between the hook and collar, shaft 19 carrying the clutch operating handle has no axial movement and therefore the operating handle remains in a constant plane relative to the floor of the boat and within easy reach of the operator.

To securely tie the entire gear to the boat and to prevent any possible warping or twisting of the various shafts out of their normal alignment, tie links 57 are provided, having one end pivotally connected to the stem of the boat at 58 and the other to the pivot pin of the hook. When the hook and appurtenant structure rises, compressing the spring 31, links 57 will swing about the pivot 58 causing the hook pivot to follow an arcuate path, as shown in dotted lines on Figure 2. Cross-head 32, by means of its slightly loose fit on the members 29, can tilt enough to permit rod 7 to swing with the link 57. The elongated slot in the bridge piece 30 gives freedom of movement to the rod at its upper end. The control shafting for the clutch collar can swing about its piv-

total connection at the universal joint 26 a sufficient distance to follow the movement of rod 7.

A modified form of independent release mechanism is shown in Figures 7 and 8 of the drawings. This comprises two levers 35 and 36, and a latch 37 to lock the levers together to act as one. In this form of the invention the stub shaft 14, carrying the clutch collar, has its squared lower end fitting into a squared bore 38 extending through shaft 39. The lower end of shaft 39 receives the squared end of shaft link 40. Lever 35 is secured to or formed on the lower end of shaft 39, and lever 36 is fast upon the upper end of a shaft section 59. Thus the two levers are positioned one above the other and connected to separate sections of the control shaft. The lower lever 36 has an upturned tongue 41 at its outer end which curves around the end of lever 35. Latch 37 is pivoted upon the end of lever 35 and is adapted to drop down over the tongue 41 to lock the levers together. When the latch is raised, lever 35 may be moved independently of lever 36 to operate the hook which it controls. When the latch is lowered, operation of the central control lever will rock the shaft section 59 and the lever 36, which through lever 35 will rotate the clutch collar to release the hook. Coupling the two levers together by means of the latch assures correct alignment of the clutch collar for proper release when the hooks are to be operated simultaneously.

While I have in the above described what is believed to be preferred and practical embodiments of the invention, it will be understood that changes may be made from the exact structure shown within the scope of the appended claims without departing from the spirit of the invention.

What I claim as my invention is:

1. In boat gear adapted to releasably couple a small boat to the davit falls of a large vessel, hooks near either end of said boat, a clutch collar adjacent each hook to lock the hooks in closed position, shafting interconnecting said collars having a control lever by means of which the shafting and clutch collars may be rotated to simultaneously release the hooks, means whereby the clutch collars may be independently rotated and the hooks independently released, said clutch collars being biased toward hook locking position, and positioning means to prevent the independent rotation of said clutch collars beyond hook release and hook locking positions.

2. In boat gear adapted to releasably couple a small boat to the davit falls of a large vessel, hooks near either end of said boat, a clutch collar adjacent each hook to lock the hooks in closed position, shafting interconnecting said collars having a control lever by means of which the shafting and clutch collars may be rotated to simultaneously release the hooks, and an extensible connection between said collars and said shafting to permit movement of the hook to relieve stress on the davit falls while maintaining the relative positions of the hook and the clutch collar.

3. In boat gear adapted to releasably couple a small boat to the davit falls of a large vessel, hooks near either end of said boat, a clutch collar

adjacent each hook to lock the hooks in closed position, shafting interconnecting said clutch collars, a sleeve rotatable with each clutch collar and rotatable relative to said shafting whereby the sleeve and clutch collar may be rotated independently of said shafting to independently release one hook, and means to cause the sleeves to rotate when the shafting is rotated to simultaneously release all of the hooks.

10 4. In a device as claimed in claim 3, said means comprising means to align the clutch collar with the shafting to ensure synchronous release of the hooks.

15 5. In boat gear adapted to releasably couple small boats to the davit falls of a large vessel, hooks near either end of said boat, a clutch collar adjacent to each hook to lock the hooks in closed position, shafting interconnecting said collars and having a control lever by means of which the shafting and clutch collars may be rotated to simultaneously release the hooks, a portion of said shafting adjacent each clutch being rotatable with said clutch collar and capable of independent rotation relative to the balance of said connecting shafting, a coupling joining said clutch collar portions of shafting and said balance of said connecting shafting having matching interfitting notches providing lost motion therebetween to limit the independent rotation of said clutch collars.

30 6. In boat gear adapted to releasably couple a small boat to the davit falls of a large vessel, hooks near either end of said boat, shock absorbing means between each hook and its attachment to the boat, a clutch collar cooperating with each hook to lock the hooks in closed position, sections of shafting interconnecting said collars and having a control lever by means of which the shafting and clutch collars may be rotated to simultaneously release the hooks, said sections of shafting adjacent each clutch collar comprising a short shaft telescopically connected to a portion of said clutch collar and provided with a coupling member having a notch in its lower end, a companion

35 40 coupling member carried by the end of the next section of shafting and having a matching notch to engage the notch in said first mentioned coupling member, whereby limited independent rotation of said clutch collars to release said hooks is permitted and said gear may move outwardly to cushion shocks on the davit falls.

45 7. In boat gear as claimed in claim 6, means to bias each clutch collar whereby the clutch collars will be normally maintained in hook-locking position.

50 8. In boat gear a hook having a pin extending therefrom, said hook being pivoted to swing in a vertical plane, a rotatable clutch collar having a gate therein to releasably engage said pin to lock the hook, means whereby said clutch collar may be rotated to place the gear in the plane of swing of said hook to release the hook, said clutch collar being biased to rotate the collar to move the gate from the plane of swing of said hook, and 55 positioning means to prevent the rotation of said clutch collar beyond hook release and hook locking positions.

HENRY E. ROTTMER.
